MAGNETIC RECORDING SYSTEM

Walter P. Huntley, Pasadena, Ray M. Chenoweth,
West Los Angeles, and Emmett M. Irwin, Pasadena, Calif., assignors to C-W-B Development Co., Los Angeles, Calif., a corporation of California

Application June 14, 1938, Serial No. 213,638

9 Claims. (Cl. 179—100.2)

Our invention relates to the art of recording and reproducing sound or similar vibrations and has particular reference to a novel magnetic recording medium upon which sound or other vibrations 5 may be recorded and from which the same vibrations may be readily reproduced. In the recording of sound or similar vibrations, as for example in the phonographic art adapted for business dictation and transcription, it has heretofore been the common practice to employ a recording medium of wax or similar material, into the surface of which will be engraved the vibrations to be recorded thereon and to be reproduced therefrom. Such wax records have distinct 10 disadvantages, particularly they are consumable, it being necessary to shave off part of the wax record each time the recording and transcription is made therefrom. Further such wax records are not permanent in that they are seriously affected by temperature changes and frequently 15 the material recorded upon such records is destroyed and lost before it can be transcribed.

Magnetic recording on the other hand possesses many distinct advantages, among which 20 are that magnetic records upon which sound or other vibration has been magnetically recorded are substantially permanent and are not consumable, being capable of being used repeatedly without the necessity of destroying any portion of the 25 metal of the recording medium. Moreover, such metal records upon which sound vibrations have been recorded magnetically will not be affected by temperature changes or by substantially any other external influence other than a magnetic 30 influence which would injure, destroy or otherwise harm the material recorded upon such medium.

Attempts have been made to record vibrations magnetically upon a magnetic record medium, 35 such as a steel wire or tape. The employment of a wire or tape as the record medium has necessitated movement of such wire or tape at a relatively high speed past a recording or translating mechanism adapted to alter the molecular arrangement in the wire or tape. The failure of 40 this character of recording medium and recording system has been due primarily to the inability to control the rapidly moving wire or tape and also to provide simple and adequate means for 45 storing the tape before and after recording thereon.

Further when employing tape or wire as the recording medium it is necessary to rewind the wire or tape each time it is desired to reproduce 50 sound or other vibrations that have been re-

corded thereon, rendering this type of mechanism extremely difficult to handle for ordinary office dictation and transcription purposes, wherein it is essential that during the period of dictation the dictator must be able to go back and listen 5 to any of the previously dictated material without loss of time and without complicated adjustment and rearrangement of the machine.

It is, therefore, an object of our invention to provide a magnetic recording medium upon 10 which a sound track may be magnetically recorded along a spiral or helical or other convolute path, in which adjacent coils or convolutions of the path may be disposed in close juxtaposition without interference between the 15 sounds recorded upon such adjacent convolutions.

Another object of our invention is to provide a magnetic recording medium as set forth in the preceding paragraph adapted to permit the concentration of relatively large quantities of 20 magnetic flux upon a minute area of the medium.

Another object of our invention is to provide a record medium of the magnetic type which substantially corresponds in form and shape to either cylindrical or disc records of the wax type now 25 in common use, to permit the handling of such records in the same manner as conventional wax records are now handled.

Another object of our invention is to provide a record medium adapted for magnetic recording 30 in which a compact, self-supporting but extremely thin recording surface is provided, adapted to be placed in a magnetic circuit of relatively low reluctance, whereby a stylus for passing magnetic flux into and through the thin skin surface may 35 present to the recording surface a relatively small area and yet pass relatively large quantities of magnetic flux through the recording medium to effect the necessary alteration of the molecular arrangement in the recording medium to permanently record sound or similar vibrations. 40

Another object of our invention is to provide a recording medium, as set forth in the preceding paragraph, in which recording styli may be employed, one on one side of the skin surface and 45 the other on the opposite side of the skin surface but accurately aligned with the first stylus to permit opposed styli each to present a minute area to the recording medium, to thus prevent the spreading out of the lines of flux as they 50 pass through the medium.

Another object of our invention is to provide a magnetic recording medium which may be constructed of such rugged character as will permit the ready handling thereof without fear of acci- 55

dental breakage, in which a relatively thin skin surface of high magnetic retentivity capable of permanently registering and retaining a magnetic pattern of sound vibrations may be mounted upon or formed upon a base structure of relatively low magnetic reluctance and relatively low magnetic retentivity, which will assist in the completion of a low reluctance magnetic circuit.

Another object of our invention is to provide a magnetic recording medium as set forth in the preceding paragraph in which the recording occurs upon and is confined to the relatively thin skin of the medium, while the body of the medium provides a path of such low magnetic retentivity and reluctance that no additional pole-piece is required to complete a low reluctance return path for the flux employed to make the record.

Other objects of our invention will be apparent from a study of the following specification, read in connection with the accompanying drawings, wherein is disclosed an embodiment of our invention particularly adapted for office dictation and transcription, although it will be understood by those skilled in this art that our magnetic recording medium and our apparatus for magnetically recording thereon may be successfully and advantageously employed for the recording of sound vibrations or vibrations of a similar character for many other uses.

In the embodiment of our invention specially illustrated and described herein Figure 1 of the drawings represents a vertical sectional view taken through a simple dictating machine employing magnetic recording medium constructed in accordance with our invention.

Figure 2 is a vertical sectional view through the dictating machine and recording medium shown in Figure 1, the section being taken along lines II--II of Figure 1.

Figure 3 is a vertical sectional view taken through a modified form of dictating machine and magnetic record embodying the principles of our invention.

Figure 4 is a vertical sectional view taken through a still further modified form of dictating machine and magnetic record constructed in accordance with our invention and illustrating the manner in which our magnetic record may be constructed in the form of a disc.

Figure 5 is a detail fragmentary sectional view of a portion of one form of recording medium which may be employed in the machine shown in Figure 4; and

Figure 6 is a detail fragmentary sectional view of a portion of a modified manner in which the recording medium may be constructed.

Referring to the drawings we have illustrated in Figs. 1 and 2 one typical form of dictating machine which may be adapted for magnetic recording upon a record having the conventional shape of a wax cylinder record, as comprising a frame 10 which may have a relatively broad flat base 11 adapted to rest upon a table, stand or other suitable supporting device to hold the machine at a convenient level. Formed upon or attached to one end of the base 11 is a vertically extending upright 12, from the upper end of which projects an elongated beam 13 disposed a considerable distance above and extending substantially parallel to the base 11.

The vertical upright 12 constitutes a bearing member on which is rotatably mounted a mandrel spindle 14 preferably having a spool-like shape providing a pair of heads 15 and 16 disposed at either of the ends to constitute suitable sup-

porting members for engaging opposite ends of a cylindrical recording medium or record 17.

The mandrel may be rotatably mounted upon the upright 12 by means of a shaft 18, formed integrally with or attached to the mandrel 14 and extending through a suitable bore 19 in the upright 12. The inner head 16 of the mandrel should be held in contacting relation against a flat inner surface 20 of the upright 12 as by means of a sprocket or pinion 21 rigidly secured upon the shaft 18 by means of a set screw 22.

Power for rotating the mandrel 14 and the recording medium 17 may be supplied in any suitable manner as by securing a pulley 23 upon the shaft 18 to receive a belt 24 driven by any desired motor or other power means.

The beam 13 constitutes a supporting bar and track-way along which a recording device 25 may move lengthwise of the recording medium 17, the recording device 25 including a carriage block 26 slidably mounted on the beam 13 as by means of a pair of gibbs 27 disposed on opposite sides of the block 26 and having ends 28 thereon extending over the upper side of the beam 13. As is illustrated particularly in Figure 2, the beam 13 may be rectangular in cross section to provide a substantially flat lower surface along which the recording device 25 will slide.

Upon the lower surface of the block 26 is mounted an electro-magnetic coil 29, having a core 30 extending therethrough, one end of the core 30 being threaded as indicated at 31 and used as a means for securing the coil 29 upon the block 26 while the opposite end of the core 30 is preferably formed as an outwardly extending stylus 32. The stylus 32 may be of relative small diameter and may have its outer end sharpened to a relatively sharp point.

As will be noted from an inspection of Figure 1 the pointed stylus 32 should be disposed immediately above the outer surface of the record cylinder 17, the spacing of the stylus from the surface of the cylinder 17 being preferably just sufficient to prevent actual mechanical contact between these members, although successful operation of our device may be accomplished if the pointed end of the stylus actually contacts with and rides upon the surface of the cylinder 17.

As is usual in the conventional dictating machine practice, the recording device should be arranged to travel longitudinally relative to the record cylinder 17 while the cylinder is rotating, so that the path described by the stylus 32 upon the surface of the record cylinder 17 will be a helix with adjacent convolutions of such helix in closely arranged parallel relation.

To accomplish the longitudinal travel of the recording device along the record we provide a feed screw 33 disposed immediately below and extending parallel with the beam 13, the feed screw being mounted for rotation by means of extending one end thereof through a bearing 34 in the upright 12 while the opposite end of the feed screw 33 extends through a bearing bore 35 in a bearing block 36 secured to the outer end of the beam 13.

The feed screw 33 is prevented from moving longitudinally relative to beam 13 as by securing upon the right hand end thereof a pinion 37 while a locking collar 38 is secured upon the left hand end of the feed screw by means of a set screw 39. The pinion 37 may be employed to rotate the feed screw 33 by meshing the pinion with pinion 21 on the mandrel shaft 18, the 75

pinion 37 being rigidly secured in driving relation upon the feed screw 33 as by means of a set screw 40.

The recording device carriage 26 is provided with a feed nut 41 formed upon or attached to a lever 42, which in turn is pivoted as by means of a pivot pin or screw 43 upon the carriage block 26. The inner end of the lever 42 is provided with a spring 44 normally urging the nut 41 into engagement with the threads of the feed screw 33, while the projecting outer end of the lever 42 constitutes a handle by means of which the feed nut 41 may be disengaged from the feed screw 33 to permit the recording device to be manually shifted along the record 17 to any desired point.

It is well known that in magnetic recording the sound or other vibrations are recorded by creating within the recording medium areas of magnetic poles of varying strength, corresponding to variations in the current which is supplied to the coil of the magnetic recording device. To permit the employment of relatively low rate of motion between the recording medium and the recording device it is essential that the area occupied by each of the poles created must be maintained as minute as possible. For this reason the thickness of the recording medium which will be permanently affected by the flux from the recording device must be maintained sufficiently small to prevent the splaying out of the flux lines as they pass into and through the recording medium. Thus by employing a stylus with a relatively sharp point, the area thereof which is presented to the recording medium 17 may be maintained extremely small and will produce sharply defined poles upon the recording medium. If, however, the recording medium is relatively thick there may be a tendency for flux lines to diverge as they pass further into the recording medium, the condition which is accentuated by any reluctance in the return magnetic circuit to the stylus.

It is important, therefore, that at least that part of the recording medium which is permanently affected by the recording flux must be maintained as thin as it is possible to make it and yet have it sufficiently strong to be self-supporting and to hold its shape. Further, it is necessary to provide a return magnetic circuit exteriorly of the thin recording part of the medium of sufficiently low reluctance to permit the concentration of large quantities of flux in a minute recording area.

One form of magnetic recording medium which will satisfy all of the foregoing conditions and yet be sufficiently strong to withstand rough handling and which may be made of a size and shape corresponding to the size and shape of conventional wax records is illustrated in Figures 1 and 2 as comprising the recording medium 17 having a cylindrical shape which may correspond in all respects to the size and shape of conventional cylinder wax records. The recording medium 17 includes a relatively thin shell or skin portion 45 formed of any suitable material having the characteristics of relatively high magnetic retentivity and thus be adapted to have created therein magnetic poles of varying strength and to retain such poles until the recorded material is to be erased. This skin surface may be made as thin as may be desired and may be supported upon the body portion 46 formed of suitable material having relatively

low magnetic reluctance and relatively low magnetic retentivity.

By making the skin surface extremely thin and by making the body portion of low reluctance the body portion may be employed as a part of the return magnetic circuit, insuring the transmission of lines of magnetic force through the thin skin surface 45 without appreciable divergence of such lines and thus permitting the creation of poles therein over an extremely minute area.

By referring particularly to Figure 1 it will be noted that the magnetic circuit for the flux emanating from the stylus 32 will include the skin or shell 45, the body 46 of the cylinder 17, 15 the mandrel 14, the vertical upright 12, the horizontal beam 13, and the carriage block 26. By constructing the mandrel 14, the vertical upright 12, the beam 13 and the carriage block 26 of material of low magnetic reluctance it is apparent that relatively large quantities of magnetic flux may emanate from the stylus 32 to permanently effect a change in the skin surface 45 of the record cylinder 17, while the remainder of the magnetic path is not permanently affected. 25

To insure that the entire magnetic path will be of low reluctance we prefer to form the internal diameter of the record cylinder 17 to closely conform with the diameter of the head 15 on the mandrel 14 and to provide an accurately machined shoulder 47 on the head 16, thus insuring adequate mechanical contact between the cylinder 17 and the mandrel 14. To hold the cylinder 17 tightly upon the mandrel 14 we provide a movable end plate 48 adapted to be secured to the mandrel 14 as by means of a thumb screw 49 or other suitable device which will prevent displacement of the end plate from the mandrel, the outer portion of the end plate bearing against the outer end of the cylinder 17 to force the same snugly against an abutment shoulder 50 on the mandrel head 16.

The transfer of the magnetic flux between the rotating mandrel 14 and the stationary upright 12 may be adequately provided for by maintaining a relatively large surface area of the head 16 in snug metallic contact with the vertical upright 12, which may be readily accomplished by inserting a spring washer 51 between the pinion 21 and the outer surface of the upright 12. 50

Employing machines and records as illustrated and described in Figs. 1 and 2, it will be apparent that our system is adapted for ordinary office dictation and transcription, merely substituting magnetic recording devices for the wax record-engraving devices now employed and substituting magnetic recording cylinders in place of the wax record cylinders now in common use. 55

In employing our magnetic record the coil 29 will be connected to a suitable microphone or other electrical pickup circuit whereby sounds such as dictation will be transformed into electrical impulses and supplied as variations of electric current to the coil 29.

To start dictation the operator of the machine 65 may elevate the outer end of the feed nut lever 42 and slide the recording device 25 toward the left to dispose stylus 32 immediately over the left hand end of the cylinder 17. By starting the motor or other power device employed to drive 70 the belt 24 the cylinder 17 will be started into rotation while at the same time the rotation of the feed screw 33 will start the recording device travelling along the length of the record. The dictator may then employ the same dictating 75

technic as is now employed for recording on wax records, dictating, pausing and resuming his dictation as desired. During pauses he may stop the rotation of the cylinder and feed screw 5 by employing the usual clutch or switch control devices provided on standard dictation machines for this purpose but which are not shown herein.

The dictator may play back any of the previously dictated material merely by lifting the lever 42 and moving the recording device back to the point along the record at which he desires to listen to the previously dictated material. The same recording device 25 may be used both for the purpose of recording and for reproducing 10 previously recorded material from the record by merely shifting the coil connections from the microphone or transmitter circuits to receiving circuits in the manner disclosed in our co-pending application Serial No. 53,396, filed December 15 1935.

When the dictator desires to resume dictation he may again lift the lever 42 and slide the recording device 25 toward the right to the point along the record 17 at which he left off dictating thus releasing the lever 42 and shifting the coil circuit back to connection with the microphone and the machine is again conditioned for further dictation.

The magnetic recording medium 17 may be 30 constructed in a number of different ways. For example, one simple and convenient manner of constructing the same is to employ a relatively thick walled tube of iron or soft steel having suitable low magnetic reluctance and low magnetic 35 retentivity and to apply upon the outer surface of such tube a shell jacket or coating of hard steel or any other magnetic material having the characteristics of being highly magnetic retentive.

Such coating or jacket may be applied by any 40 method adapted to the particular characteristics of the material from which it is made. Thus, certain materials such as hard steel may be machined into shells of relatively thin walls and shrunk upon the soft iron or steel body portion, or suitable magnetic material may be plated upon or sprayed upon the outer surface of the body portion 46 and then ground, machined or otherwise smoothed to provide a smooth surface for presentation to the stylus 32.

Another convenient manner in which recording medium may be constructed is to form a 50 suitable length of tube of soft steel and then to harden the outer surface thereof by any suitable process by which the depth of which said material will be hardened may be controlled.

In all such forms the recording portion of the medium comprises a thin sheet or sheet-like member, the length and breadth (circumference) 55 dimensions of which are of like or comparable order of magnitude as distinguished from those of a wire or tape and which therefore provides a compact uniform surface area over which the stylus may describe a convolute path, adjacent convolutions of which may be arranged close together.

For example, the speed of rotation of the record 17 and the pitch and speed of the feed screw may be so selected that adjacent coils of the helical path described by the stylus may be arranged 70 extremely close to each other. The only limitation is that the poles created in adjacent coils must not interfere with or affect each other. Adjacent poles in a single line of recording may be made as close together as 0.005 inch and it follows that adjacent coils of the helix

may be placed at 0.005 inch or slightly more apart with successful result. Thus a relatively small diameter and relatively short cylinder may have a sufficient capacity to hold a great quantity of recorded dictation. Also, if desired, a 5 helical groove may be preformed in the surface of the cylinder as shown at X in Fig. 1 in which the recording or reproducing stylus may track to insure accuracy of spacing of the adjacent coils or convolutions of the recorded material and 10 to insure correct tracking of the stylus on a transcription machine which may be used to transcribe the material.

In Fig. 3 we have illustrated a modified form of our magnetic recording medium and machine 15 which is easily adapted for sharply defined magnetic recording even though adjacent convolutions of recorded material may lie extremely close to each other. In this form of device we have illustrated a machine having a frame 52 including a suitable base 52a and a vertically extending upright post 52b formed thereon. The post 52b may constitute a bearing member in which is rotatably mounted a suitable record support 53, constructed substantially in the form of a 25 face plate the hub of which may be secured to or formed integrally with a shaft 54. The shaft 54 may be driven in any suitable manner as by means of a belt 55 extended over a pulley 56 which is rigidly secured upon the shaft 54 while 30 endwise motion of the record support 53 will be prevented by butting the hub of the support 53 upon one side of the upright 52b and employing a pinion 57 secured upon the shaft 54 and abutting the opposite side of the upright 52b. 35 A beam 58 corresponding in substantially all respects to the beam 13 may extend from the upper end of the upright 52b to be disposed in spaced parallel relation above the base 52. A suitable feed screw 59 may be mounted immediately below the beam 58 in the same manner as was described for the mounting of the feed screw 33, such feed screw being driven by means of a pinion 60 meshing with the pinion 57.

The recording device in this form of our invention includes a carriage 61 slidably mounted upon the beam 58 for movement longitudinally relative to a record 62, the carriage 61 being provided with suitable feed nut and lever mechanism, corresponding to the feed nut 41 and lever 42 described with reference to Figures 1 and 2. Secured to or formed integrally with the carriage 61 is a substantially U shaped stylus support 63, one leg of which extends substantially parallel to the base 52a and is disposed above the record 62 while the other leg extends parallel to the first leg but is disposed at a sufficiently lower level to permit its introduction into the interior of the hollow record cylinder 62.

The upper leg 64 mounts a recording stylus 66 having a coil 67 surrounding the same, the stylus and coil being constructed in all respects identical with the coil and stylus described with reference to Figure 1. The lower leg 65 may be merely provided with a pole piece aligned immediately below the sharpened or pointed end of the stylus 66 or as is illustrated in Figure 3 such pole piece may take the form of an opposing stylus 68 provided with an energizing coil 69 so that current is supplied from the microphone circuit to both coils 67 and 69 to cause magnetic flux to pass from the stylus 66 through the record 62 and to the stylus 68, or vice versa, the return magnetic circuit being completed through the legs and base of the U shaped stylus 75

support which should be constructed of material having relatively low magnetic reluctance and low magnetic retentivity.

In the form of the device illustrated in Figure 5 3 the record 62 is constructed solely as a relatively thin shell of suitable magnetic material having high magnetic retentivity, thickness of the walls of which is preferably such that little or no divergence of the lines of magnetic 10 force will be permitted during the passage of the flux from one of the styli to the other. Depending upon the characteristics of the particular material selected for the record cylinder 62 the walls should be made as thin as possible and yet 15 provide sufficient strength in the walls to retain their cylindrical shape and be self-supporting.

One end of the record 62 is attached to the record support 63 by any suitable means which 20 will support the cylinder for rotation about its longitudinal axis, one form of attachment being illustrated herein as comprising a plurality of spring fingers 70 distributed about the record support 53 and projecting over the outer surface 25 of the record cylinder 62 to frictionally engage the same so that rotation of the record support 53 will cause rotation of the cylinder 62.

If desired the spring fingers 70 may be bent 30 inwardly as shown in Figure 3 to provide projections extending into an annular groove 71 formed about one end of the cylinder 62, and thus prevent inadvertent longitudinal displacement of the record and the record support. The 35 end of the record cylinder bearing the groove 71 may be thickened, if desired, as shown at 72.

If desired, the opposite end of the cylinder may be supported and held in horizontal alignment by means of a bearing block 73 rotatably mounted upon the lower leg 65 in which event 40 leg 65 should be constructed as a round rod or shaft upon which the bearing block 73 is readily rotated and along which it may slide. The block 73 may be detachably secured to the end of the cylinder 62 as by providing a plurality of spring 45 fingers 74 thereon projecting inwardly of the cylinder 62 to engage a groove 75 formed internally within the cylinder. That portion of the cylinder walls bearing the groove 75 may be thickened as is indicated at 76. To prevent undesired magnetic paths the cylinder support 53 and the bearing block 73 should be constructed of 50 non-magnetic material.

In this form of the device the cylinder 62 may be placed in the machine by first moving the 55 carriage 61 to its extreme left hand position as viewed in Figure 3 and the cylinder 62 may be then pressed between the spring fingers 70 into abutting relation with the cylinder support 53. Then the carriage 61 is moved toward the 60 right to insert stylus 68 and the arm 65 within the interior of the cylinder. The bearing block 73 may be slid along the arm 65 into engagement with the opposite end of the cylinder 62. The carriage 61 is then moved toward the left to 65 dispose the styli 66 and 68 upon the left hand end portion of the record 62. The dictator may then start dictating and the relative rotation between the cylinder 62 and the styli 66 and 68 and the longitudinal movement of the carriage 70 70 75 will cause the styli 66 and 68 to describe a helical path about the cylinder 62 to record the dictated material thereon in the same manner as was described with reference to Figures 1 and 2.

75 While the styli 66 and 68 may be disposed

in spaced relation to the inner and outer surfaces of the cylinder 62, they may be arranged to bear upon and ride directly upon the surface of the cylinder, in which event it may be desirable to mount both of the styli on suitable springs 5 not shown which will cause them to be urged gently against the cylinder surfaces, such mounting of the styli permitting the ready retraction of the stylus 68 as it is withdrawn from the cylinder 62 and passes over the thickened portion 10 15 16 thereof.

During dictation any portion of the previously dictated material to which it is desired to listen may be played back by the dictator by merely lifting the feed nut from the feed screw 59 and 15 moving the carriage 51 toward the left to align styli 66 and 68 with such previously recorded material. The coils 67 and 69 may be connected to suitable receiving apparatus by which the dictator may listen to the previously dictated material, in much the same manner as was described 20 with reference to the form of device shown in Figs. 1 and 2.

In Fig. 4 we have illustrated a still further modified form of magnetic recording medium and 25 machine embodying the principles of our invention and illustrating the manner in which the recording medium may be constructed in the shape of a disc corresponding in size and shape 30 to the wax disc records now employed in phonographic recording and reproduction. In Fig. 4 we have illustrated our machine as comprising a suitable frame 80 which includes the base 81 from which arises a vertical standard 82 and a second vertical standard 83. The standard 83 35 may constitute the bearing mounting for a disc supporting turntable 84 which may be permanently or detachably connected to a centering head 85 secured to or formed integrally with a shaft 86. 40

The shaft 86 is adapted to be connected for rotation by any suitable power means as by a transmission system illustrated herein as including a bevel gear 87 fixed to the shaft 86 and meshed with a cooperating bevelled gear 88 45 secured upon a cross shaft 89 rotatably mounted in the uprights 80 and 82. The outer or right hand end of the shaft 89 as viewed in Fig. 4 may be provided with a bevelled gear 90 which in turn meshes with a bevelled gear 91 fixed to 50 one end of a stub shaft 92 which is rotatably mounted in the upright 82 and having on its opposite end a gear 93 meshed with a gear 94 rigidly secured to a power shaft 95. Power may be supplied to the power shaft 95 through a suitable pulley 96 and drive belt 97 in the conventional manner now employed for driving dictation machines. 55

The upper end of the upright 82 is provided with a longitudinally extending beam 98 corresponding in all respects with the beam 13 illustrated and described in the form of the device shown in Figs. 1 and 2, along which is arranged to slide a carriage 99 bearing the recording stylus or styli. 60 65

Again it will be noted that the carriage 99 is provided with nut 100 and an operating lever 101 corresponding in all respects to the feed nut 41 and lever 42 shown in Figs. 1 and 2, by which the carriage may be selectively engaged with a feed 70 screw 102 which extends below beam 98. The feed screw may be formed integrally with the power shaft 95.

The carriage 99 has secured thereto or formed integrally therewith a U shaped stylus support 75

- 103 which may comprise an upper leg 104, a base 105 and a lower leg 106. As illustrated the upper leg and lower leg 104 and 106 should be so located as to be disposed respectively above and below a record disc 107. The upper leg 104 is provided with a recording stylus 108 having a sharp pointed end such as was described for the recording stylus 32 in Fig. 1, while the lower leg 106 bears a corresponding stylus 109 aligned with 5 the stylus 108 in the same manner as previously described for the alignment of styli 66 and 68 with reference to Fig. 3. The stylus support 103 should be constructed of material having relatively low magnetic reluctance to constitute a low reluctance magnetic path for flux which may be produced at any point in the magnetic circuit by providing an electro-magnetic coil 110, illustrated herein as extending about the base portion 105 of the U shaped stylus support 103.
- 10 One convenient manner of mounting the coil 110 is illustrated herein as by constructing the base 105 of the stylus support 103 separate from one of the legs 104 or 106 and detachably connecting the same thereto by means of a screw 20 or bolt 111.

In this form of the device the magnetic record or recording medium 107 may have the shape of a relatively thin but relatively large diameter circular disc, removably mounted on the turn-table 84, and may be constructed in the manner described for the construction of the record 72 shown in Fig. 3, that is, as a sheet of material of high magnetic retentivity as thin as it is possible to make it and yet be capable of holding 30 its flat disc shape and to be self-supporting, or the record disc 107 may be constructed as shown in Figs. 5 and 6 with a body portion or supporting portion 112, sufficiently thick as to lend rigidity to the disc but provided upon one or both of its faces with a thin layer 113 and 113a of materials having high magnetic retentivity so as to adapt it to receive and hold magnetic patterns produced by flux passing between the stylus 108 and 109.

45 In either event the magnetic flux produced by the coil 110 will pass directly through the recording portion of the record 107 to record the magnetic pattern corresponding to the dictation.

If the record disc 107 is constructed as an extremely thin sheet of high retentive material the recording made thereon will correspond to the recording made as by the use of a record like that shown at 62 in Fig. 3. If, however, the 50 record disc 107 is constructed with a body or supporting portion having a thin shell or coating of high retentive material on one face thereof, the body portion 112 should be made of low reluctance material to assist in providing a low 55 reluctance return magnetic circuit to the stylus 108. With the record constructed in this manner the lower stylus 109 may be made as a relatively large area pole piece or may be omitted as shown in Fig. 5, in which event the lower leg 106 of the stylus support 103 may be moved up 60 into close juxtaposition with the disc 107. If, however, as is shown in Fig. 6, both surfaces of the supporting portion 112 are provided with a highly retentive material 113 and 113a the lower 65 stylus 109 will co-act with the stylus 108 to insure the passing of the lines of magnetic flux in a direct vertical path through both of the highly retentive layers on the disc, even through the 70 lines of flux may tend to spread out as they pass 75

through the low reluctance supporting portion of the record.

As will be understood by those skilled in the art of magnetic recording any of the magnetic records shown in Figs. 1 through 6 may be initially prepared for receiving recordings thereon by polarizing the records uniformly or by magnetically saturating the records as by passing them through the influence of a strong magnet, so that during the recording of material upon 10 the record the flux passing from or between the various stylus will be permitted to rearrange the molecules of the metal to create a magnetic pattern corresponding to the sound to be recorded thereon. It will also be understood that any of 15 the machines described herein may be used both for dictation and for transcription of previously dictated material without the necessity of moving the records from one machine to another, and that after the material has been transcribed 20 the recordings may be erased by passing the records again through the influence of a strong magnetic field, one manner of erasing such material being illustrated in our co-pending application hereinbefore referred to.

25 From the foregoing description it will be apparent that we have provided a simple and economical means for producing magnetic records or recording media which may have the simple, compact shape now employed in the conventional 30 wax record for dictating, transcribing or phonographic machines and which may be handled with the same facility with which such wax records are now handled in conventional machines. Our magnetic records however have the 35 additional advantages that the recordings thereon are permanent until erased by a magnetic field and are not subject to consumption by repeated recordings and erasures.

Another advantage which may be achieved 40 by the use of our magnetic records is that any of the previously dictated material is available to be played back without the necessity of reversing the operation of the machine or by performing any other complicated rewinding operations which have heretofore been necessary in attempts to employ magnetic recording for this purpose. The entire recorded material lies upon the surface of the recording medium and is instantly available for playback merely by the 45 shifting of the stylus along the record to the position at which it is desired to playback the recorded material.

50 While we have illustrated and described the preferred embodiment of our invention we do not desire to be limited to any of the detail shown or described herein except as defined in the appended claims.

55 We claim:

1. A magnetic recording medium having the 60 form of a thin sheet of highly retentive magnetic material supported throughout upon a stiffening body of low reluctance magnetic material, said surface having a convolute groove formed therein 65 to guide a magnetic recording stylus in an accurate convolute path over said surface.

2. A magnetic recording medium including a supporting body portion formed as a disc of low reluctance magnetic material and a thin coating 70 on at least one of its faces formed of highly retentive magnetic material.

3. A magnetic recording medium comprising a body portion constructed of low magnetic reluctance material having low magnetic retentivity and carrying a thin surface portion of 75

high magnetic retentivity integral with said body portion.

4. A magnetic recording medium comprising a body portion constructed of low magnetic reluctance material having low magnetic retentivity and having a thin surface portion of harder material to provide a highly magnetically retentive surface integral with said body portion.

5. A magnetic recording medium comprising a soft iron body portion having low magnetic reluctance and low magnetic retentivity, at least one surface of which is provided with a thin, hard surface layer of high magnetic retentivity integral with said body portion.

10 6. A magnetic recording medium comprising a low carbon content iron body portion having low magnetic reluctance and low magnetic retentivity, at least one surface of which is provided with a thin surface layer integral with said body portion and having a carbon content substantially greater than the carbon content of said body portion to provide a highly magnetically retentive layer.

7. A magnetic recording medium comprising a soft iron body portion having low magnetic reluctance and low magnetic retentivity, at least one surface of which is case hardened to provide an integral surface layer of highly magnetically retentive material. 5

8. A magnetic recording medium comprising a body portion of para magnetic material and a surface layer integral therewith, said surface layer and said body portion having dissimilar 10 magnetic properties.

9. A magnetic recording medium comprising a body member constructed of low magnetic reluctance material having low magnetic retentivity, at least one surface of which has been 15 processed to provide a thin surface layer having high magnetic retentivity.
